UNITED STATES PATENT OFFICE.

FREDERICK D. GARDNER, OF ST. LOUIS, MISSOURI.

BURIAL-CASKET.

1,053,907.

Specification of Letters Patent.

Patented Feb. 18, 1913.

Application filed November 15, 1911. Serial No. 660,536.

To all whom it may concern:

Be it known that I, FREDERICK D. GARDNER, a citizen of the United States, and resident of St. Louis, Missouri, have invented 5 certain new and useful Improvements in Burial-Caskets, of which the following is a specification containing a full, clear, and exact description, reference being had to the accompanying drawings, forming a part 10 hereof.

My invention relates to burial caskets, and consists in the novel construction hereinafter described and claimed.

The object of my invention is to provide 15 an improved octagonal burial-casket, whereby the interior draping or lining will be automatically moved in front of the unsightly and objectionable cut-away corners of the casket and lid and act as a screen 20 to conceal the same from view whenever the lid is opened; and thereby render the casket less gruesome to sensitive and to artistic mourners and friends.

In the drawings: Figure 1 is a front perspective view of a burial casket having my 25 invention applied thereto, portions being broken away to economize in drawing space; Fig. 2 is a rear perspective view of the same; and Fig. 3 is an end elevation of the same;

30 The numeral 1 indicates the casket, which may be of any of the usual forms having what are known as "octagonal" ends, and it is provided with the usual lid 2, hinged at one side to said casket.

35 The four corners of the casket 1 and its lid are necessarily cut away at 3, in order to match, thereby leaving a triangular space 4 at the intersection of the casket and its

lid. Heretofore this triangular space has presented to sensitive natures a somewhat 40 unsightly or offensive appearance, and to avoid this objectionable feature I extend the internal lining 5 continuously across the unsightly triangular space 4, so that said lining will present an unbroken appearance at 45 the point where it crosses over the said triangular space, and in a great measure avoid said objectionable feature. The lining 5 is secured in position by the usual tacks and other fastenings, which need not be shown 50 or described.

The operation of my invention is very simple, and need not be further described except to say that when the lid 2 is opened the lining 5 will be extended across the triangular space 4 as shown in the drawing, and when the lid is closed the said lining will be folded within the casket without interfering with the action of the lid.

What I claim is:

The improved burial casket, comprising 60 a body, a lid hinged to said body and both body and lid having matched octagonal ends, and a lining secured to the lid and arranged to open with said lid and act as a 65 screen to conceal the unsightly triangular spaces between the ends of said body and lid, whenever the lid is opened.

In testimony whereof, I have signed my 70 name to this specification, in presence of two subscribing witnesses.

FREDERICK D. GARDNER.
